CARD TABLE

Application filed November 4, 1929. Serial No. 404,535.

My present invention relates to card tables and more particularly to the manner of joining or hingedly connecting the legs to the table top so that the legs may be moved outwardly or extended when the table is in use or may be collapsed or folded flat against the table top to provide a compact structure for storage.

It is at present the practice in constructing card tables to hinge the legs to the top by means of a pivotal bolt and also to provide a sliding or a hinged diagonal brace that connects the top and the leg at points spaced from the pivotal bolt. Various means have been provided for insuring the locking of the parts in both their opened or closed positions, and these means are more or less dependable but they require manipulation to cause the interlocking portions to interengage, which, in many instances, causes injury to the user's hands while performing such operation.

With my present structure I have provided a comparatively simple combination of parts that effectively maintain the table legs in proper relation to the table top in their opened and their closed positions and such parts are released merely by the action of moving the leg from one position to the other. In both the opened and the closed positions of the legs they are maintained in a rigid manner with respect to the table top and the locking or releasing of the parts in either position is what might be termed automatic because it requires no manipulation on the part of the user other than to move or swing the leg. Furthermore, I have avoided the use of diagonal braces, or stays of a similar nature, and the parts are simple in design so that they will not increase the weight or cost of the card table.

I have numerous other objects in view, among which are the provision of devices of the character described that are novel in the construction and arrangement of the parts, are easy to operate, are effective in performing their functions, and which are economical to produce. I prefer to carry out my invention, and to accomplish the objects thereof, in substantially the manner herein-after fully described and as more particularly

pointed out in the appended claims, reference being herein made to the accompanying drawing that forms a part of this specification.

In the drawing:

Figure 1 is a fragmentary sectional view of a corner of a card table, showing my invention applied thereto, parts of my leg-attaching devices being in side elevation.

Figure 2 is a vertical transverse section taken on line 2—2 of Figure 1, and looking in the direction of the arrows.

Figure 3 is a horizontal section on line 3—3 of Figure 1, looking in the direction of the arrows.

Figure 4 is an elevational view of the operating face of the element that is secured to the leg.

Figure 5 is a similar view in elevation of the element that is secured to the table.

The drawing is to be understood as being more or less schematic for the purpose of illustrating a typical or preferred form in which my invention may be made, and in said drawing similar references have been employed to designate the same parts wherever they appear throughout the several views.

In the structure shown in the drawing the top of the table comprises a flat piece or plate 5 that may be a veneer or other suitable material that is of rectangular form and of such dimensions as may be desired for the table. The plate 5 is secured by means of brads or otherwise to an open frame consisting of parallel longitudinal strips 6 and parallel transverse strips 7 that are secured providing the supporting rails together at their ends in any suitable manner. The legs 8 are strips of suitable rectangular cross section and they are of sufficient length to support the table top, when in use, at the desired height above the floor. The legs 8 are pivotally or hingedly connected to the rails of the frame at the corners of the table.

As the hinging structures at the corners of the table are all similar a single unit will be described. The hinge element which I provide for connecting a leg to the table top is in the form of a bolt 9, the elongated shank of which passes transversely through the adjacent transverse strip or frame rail 7 and

through the adjacent end of the leg 8. In order to support the inner end of the bolt I mount an angle bracket on the adjacent longitudinal strip or frame rail 6 by means of screws 10. This bracket is preferably a piece 5 of angle metal one member 11 of which engages the inner face of the longitudinal rail 6 and the lateral member 12 of which extends away from the rail and alongside the leg where it is provided with an aperture through 10 which the adjacent end of the bolt 9 passes. A nut 13 secures the parts in assembly. The angle bracket and bolt are mounted on the rail adjacent or at the corner of the table. 15 The flat metal plate 14 is secured longitudinally to the end of the leg 8 and where the said plate is disposed between the rail 7 and the lateral member 12 of the bracket it is provided with an elongated rib or tenon 15 extending longitudinally of the plate upon the 20 surface thereof adjacent or facing the lateral member 12 of the bracket. The opposing face of bracket member 12 is provided with a longitudinal groove 16 and a transverse groove 25 17 that intersect each other at the aperture where the bolt 9 passes through the member. These grooves are preferably of counterpart formation with respect to the rib 15 so that when the leg is in a vertical position to support 30 the table top the rib 15 of the plate will be seated in the vertical or transverse groove 17 of the bracket member, and when the leg is folded into a closed or collapsed position the horizontal or longitudinal groove 16 will be engaged by the rib 15 on the leg plate. 35

The grooves and the rib are of sufficient dimensions to insure a positive locking of the parts when they are interengaged, and in order to yieldably urge the parts into interlocking relation I interpose a spring between 40 the rail carrying the bolt and the leg mounted on said bolt. The yieldable means which I have shown is a coiled expansion spring 18 that is disposed in a pocket 19 formed horizontally in the rail 7 surrounding the bolt 9 and having its open portion facing towards the leg. If desired a washer 20 may be seated in the inner end of the socket 19 and another washer 21 may be placed against the leg during 45 the assembly of the parts. The urge of the spring 18 causes the leg plate 14 to press towards the bracket member 12 and when the rib 15 is in either of the grooves 16 or 17 of the bracket member the parts will be firmly interlocked and the leg is maintained 50 against accidental movement.

From the foregoing it will be seen I have provided a dependable means for connecting a leg hingedly to a table top, which means 60 permit the leg to be extended or opened and held in such position against accidental displacement, and when the leg is collapsed or folded flat against the table top the leg will be dependently maintained in the latter position. It should be noted that I accomplish

these functions without the use of diagonal braces or similar stays and the legs may be readily manipulated by grasping them, preferably, near their free ends in order to overcome the yieldable interlocking action created 70 by the expansion of the spring which forces the rib 15 into the respective groove. It will be understood, of course, that modifications may be made without departing from the principles involved. It should be further understood that the drawing and detailed description herein given are for the purpose of clearness of understanding only and no unnecessary limitations are to be understood 75 therefrom, but the appended claims are to be construed as broadly as permissible in view 80 of the prior art.

What I claim is:—

1. The combination with a table having side-rails arranged at angles to each other, of an angle-bracket one arm of which is secured to a side-rail and the other arm projects therefrom parallel with and spaced from the adjacent side-rail, a hinge-bolt extending from said adjacent side-rail through the projecting arm of said bracket, a leg pivotally mounted at one end on said bolt, a latch-plate on the upper portion of said leg with a surface opposed to a surface of the projecting arm of said bracket, a tenon and groove on the opposing surfaces of said arm and plate, and a spring interposed between said leg and said adjacent side-rail for urging the leg structure towards said projecting arm of the bracket. 95

2. The combination with a table having side-rails arranged at angles to each other, of an angle-bracket one arm of which is secured to a side-rail and the other arm projects therefrom parallel with and spaced from the adjacent side-rail, a hinge-bolt extending from the projecting arm of said bracket, a leg pivotally mounted at one end on said bolt between said projecting arm and said adjacent side-rail and one of the opposing portions of said elements provided with a recess around said bolt, a latch-plate on the upper portion of said leg with a surface opposing the surface of the projecting arm of said bracket, a tenon and groove on the opposing surfaces of said arm and plate, and a coiled expansion spring seated in said recess and surrounding said bolt and urging the leg structure towards said projecting arm to cause interengagement of said tenon and groove. 110

Signed at Chicago, in the county of Cook and State of Illinois, this 26th day of July, 1929.
